(57) **CLAIM**

The ornamental design for a dryer machine, as shown and described.

DESCRIPTION

FIG. 1 is a front, top, and right-side perspective view of a dryer machine;

FIG. 2 is a right-side elevation view thereof;

FIG. 3 is a left-side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a front, right-side perspective view thereof;

FIG. 9 is a front, right-side perspective view with a second environment;

FIG. 10 is a front, right-side perspective view with a third environment; and,

FIG. 11 is a rear, right-side perspective view thereof.

The broken lines shown in the drawings are shown for illustrative purposes only and form no part of the claimed design. In addition, the surface shading, if any, illustrated in the drawings is provided merely to highlight the contour of the design; it is not intended to be illustrative of texture or gloss.
